UNITED STATES PATENT OFFICE.

MELCHIOR ZWICKY, OF WYOMISSING, PENNSYLVANIA, ASSIGNOR TO TEXTILE MACHINE WORKS, OF WYOMISSING, PENNSYLVANIA, A CORPORATION OF PENNSYLVANIA.

KNOCK-OVER-BIT MECHANISM FOR KNITTING-MACHINES.

1,150,567.

Specification of Letters Patent. Patented Aug. 17, 1915.

Application filed December 27, 1913. Serial No. 808,932.

To all whom it may concern:

Be it known that I, MELCHIOR ZWICKY, a citizen of the United States, residing at Wyomissing, in the county of Berks and State of Pennsylvania, have invented certain new and useful Improvements in Knock-Over-Bit Mechanism for Knitting-Machines, of which the following is a specification.

My invention relates to straight or full-fashioned knitting machines, and more particularly to improved knock-over-bit mechanism therefor as hereinafter fully described in connection with the accompanying drawings and the novel features of which are specifically pointed out in the claim.

The object of my invention is to provide against objectionable slackening of the yarn during formation of the loops, and thereby improve the quality of the knitted fabric. Such slackening is ordinarily incident particularly to the freeing of the loops by the action of the knock-over-bits, and effort has heretofore been made to overcome this by intermittently shifting the latter relative to the loop forming devices. My invention provides an improved mechanism for this purpose as hereinafter fully described.

Figure 1 is a cross-sectional view showing my improved mechanism applied in preferred manner to a straight knitting machine of ordinary construction. Fig. 2 is a corresponding partial plan view. Figs. 3, 4, and 5 are enlarged cross-sectional views showing the pivotally carried knock-over bit bed in several positions assumed during operation of the machine, with corresponding positions of the co-operating sinkers and dividers. Figs. 6, 7, and 8 are separate views of the fixed sinker-and-divider bed; and Figs. 9, 10, and 11 are separate views of the rockably mounted knock-over-bit bed.

Figs. 1 and 2 indicate such portions of an ordinary straight knitting machine as are necessary to a showing of my improved knock-over-bit mechanism in connection therewith; the usual cam-shaft 2 being indicated as the means through which the required intermittent rocking movement is imparted to my pivotally mounted knock-over-bit carrier bed 3, and the machine frame 4 as the support for my pivot-bearing sinker-and-divider bed attachment, and for the rocking-lever mechanism employed.

The pivot-bearing attachment, as shown, comprises a longitudinally extending sinker-and-divider bed 10, in which the usual transversely-movable sinkers and dividers 11 and 12 are mounted; and end bearing lugs 13 in which is rockably mounted the knock-over-bit carrier bed 3. The latter has end bearing arms 14, 14^a engaged in said bearing lugs 13, and the projecting end of one of these arms, 14, has a depending lever 15 fixed thereto through which a rocking movement is imparted to the carrier bed 3 as hereinafter described. The series of knock-over bits 16 is fixed to the carrier bed so that their extended end portions stand normally at an angle of approximately forty-five degrees to the pivotal center of the carrier bed, and are adapted to swing in an arc 17 toward and away from the transversely moving sinkers and dividers with which they co-operate in the knitting operation. The bed 10 is fixedly secured to the machine frame by means of bolts 18 as indicated, and the sinker and dividers mounted therein are operated as usual.

The pivot-bearing lugs 13 of the attachment 5 depend from the end portions of the sinker-and-divider bed 10 thereof, and form in connection with the detachable bearing caps 20, pivot bearings the centers of which are located under the sinkers and dividers and well inside of the extremities of the latter as indicated; so that the knock-over bits 16, which are secured in the pivotal carrier bed 3, are swung by the rocking of the latter to varying co-operating positions relative to the sinkers and dividers 11-12, as herein-after described in connection with Figs. 3, 4, and 5.

The lever mechanism employed to transmit the desired rocking movements to each carrier-bed 3 and its series of knock-over-bits 16, comprises a cam-contacting lever 25 which is held in contact by a spring 26, with the periphery of a cam disk 27, or 27^a, having a projection 28, or 28^a, which imparts a determined swing to said lever during a determined portion of the regular rotation of cam shaft 2. This swing is transmitted through a link 30 to a rock-shaft 31 having arms 32 and 33, the latter of which is connected by a link 34 to the fixed arm 15 on the carrier bed 3, thereby rocking the

- latter so as to swing the knock-over bits to different positions desired relative to the sinkers and dividers. As will hereafter further appear these relative positions should 5 be varied to meet different conditions occurring; the knitting of ladies' stockings for instance involving the use of a welting bar in starting the stocking and forming a double top or welt, which necessitates the 10 providing of a somewhat greater space between the bottom edges of the sinkers and dividers and the top edges of the knock-over bits, than is requisite during the ordinary knitting, so that a different rocking of the 15 knock-over bit carrier bed should be provided for during these different periods of knitting in order to secure under all conditions the desired advantage of the nearest practicable approach of the knock-over bits 20 for the freeing of the loops. To accomplish this I employ the two cam disks 27 and 27^a, the lever-swinging projections 28, 28^a of which vary somewhat in height and location, as indicated, so as to differently swing the 25 lever 25 as required; at the same time providing means for conveniently shifting said lever to one or other of said cam disks. This means comprises, as shown, a shifting lever 40 loosely pivoted at 41 to the machine 30 frame so as to slide a shaft 42 having fixed thereto a shifting fork 43 adapted to engage and shift the anti-friction roller 44 of the lever 25 to one or other of the cam disks as desired. 35 Several of the positions to which the knock-over bits are swung at different stages of the knitting operation, with relative positions of the sinkers and dividers, are indicated in enlarged Figs. 3, 4, and 5. Fig. 3 40 indicates a maximum clearance between the sinkers and knock-over bits. Fig. 4 indicates a position when the welting bar is em-

ployed, the lever 25 being then in engagement with the cam disk 27^a, a lesser rocking movement is imparted to the knock-over bit 45 carrier bed 3 when the cam projection 28^a operates said lever, whereby the bits are moved to a closer position as indicated; this closer position being as near as is permissible during the knocking off of the first few 50 courses of the welting operation and so freeing the loops without any unnecessary slackening of the threads. In Fig. 5 however the bits are shown as swung still closer to the sinkers than in Fig. 4, as is practicable during ordinary knitting; the lever 25 being then in operating engagement with the larger cam projection 28 of disk 27. This pivotal swinging of the knock-over-bit bed 3 upon its bearings 14, 14^a permits of 60 always keeping the rear hump of these bits as close as possible to the forward end of the sinker-and-divider bed 10, against which the needle beards are pressed, as shown, while providing the varying clearances of the 65 outer end of these bits 16 from the sinkers and dividers 11 and 12, for the better knocking off of the formed loops without undue slack.

What I claim is:—

In a full fashioned knitting machine comprising movable needles, sinkers, and dividers; a frame-secured attachment forming a sinker-and-divider bed and provided with bit-carrier bed bearings, a knock-over-bit 75 carrier bed rockably mounted in said bearings, and means for imparting an intermittent rocking movement to said carrier bed.

In testimony whereof I affix my signature in presence of two witnesses.

MELCHIOR ZWICKY.
